US00D809552S

(12) **United States Design Patent** (10) Patent No.: **US D809,552 S**
Dye et al. (45) Date of Patent: **** Feb. 6, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Alan C. Dye**, San Francisco, CA (US);
Jonathan P. Ive, San Francisco, CA (US); **Wan Si Wan**, Sunnyvale, CA (US); **Christopher Wilson**, San Francisco, CA (US)

(73) Assignee: **Apple Inc.**, Cupertino, CA (US)

(**) Term: **15 Years**

(21) Appl. No.: **29/606,297**

(22) Filed: **Jun. 2, 2017**

Related U.S. Application Data

(63) Continuation of application No. 29/572,566, filed on Jul. 28, 2016, now Pat. No. Des. 788,807, which is a continuation of application No. 29/501,086, filed on Sep. 1, 2014, now Pat. No. Des. 762,691.

CLAIM

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
